UNITED STATES PATENT OFFICE.

WILLIAM E. WINN, OF HAMBURG, NEW YORK, ASSIGNOR TO THE STEEL STORAGE AND ELEVATOR CONSTRUCTION COMPANY, OF BUFFALO, NEW YORK.

DESIGN FOR A TANK-FLOOR.

SPECIFICATION forming part of Design No. 30,373, dated March 21, 1899.

Application filed February 9, 1899. Serial No. 705,117. Term of patent 14 years.

To all whom it may concern:

Be it known that I, WILLIAM E. WINN, of Hamburg, Erie county, New York, have invented and produced a new and original Design for Tank-Floors, of which the following is a specification, reference being had to the accompanying drawings, forming part thereof.

Figure 1 is a plan view of a tank-floor, showing my new design; and Fig. 2 is a vertical sectional view taken on the line α of Fig. 1.

As shown in the drawings, the leading or material feature of my design consists of a circular boundary A, diametrically across which is disposed the angular ridge B, to each side of which are disposed members C, sloping from the boundary A downwardly toward the base of the ridge B, thus producing a pair of parallel valleys disposed as chords of the boundary-circle, the bases of members C and

the ridge B being on the same horizontal plane, but somewhat separated from each other. Across each of these valleys and at right angles to them are disposed minor ridges D, whose bases are somewhat separated from each other and are in the horizontal plane of the bases of ridge B and members C, ports E thus being formed between the bases of the minor ridges D and the ridge B and members C.

Having described my invention, what I claim as new, and desire to secure by Letters Patent, is—

The design for a tank-floor, as herein shown and described.

WILLIAM E. WINN.
